UNITED STATES PATENT OFFICE.

SAMUEL H. McCACKEN, OF NEW KENSINGTON, PENNSYLVANIA.

ATTACHMENT FOR ACCOUNTING-MACHINES.

1,382,999.

Specification of Letters Patent. Patented June 28, 1921.

Application filed March 12, 1920. Serial No. 385,210.

To all whom it may concern:

Be it known that I, SAMUEL H. McCACKEN, a citizen of the United States, residing at New Kensington, in the county of 5 Westmoreland and State of Pennsylvania, have invented a new and useful Attachment for Accounting-Machines, of which the following is a specification.

This invention relates to an attachment 10 for use in connection with accounting machines and more particularly in connection with machines known as the "Remington Wahl."

In machines of the type mentioned and one 15 form of which has been shown, for example, in Patent No. 1,293,219 issued to W. D. Sheldon there are used adding devices or totalizers that are mounted on the actuator rack. It has been found, however, that where more 20 than two or three of these totalizers are mounted on the rack said rack is caused to sag with the result that the keys will stick and the machine will often lock. At times the pressure or strain causes the teeth to 25 break off on the totalizers.

One of the objects of the present invention is to provide means whereby a number of totalizers can be mounted on the rack without interfering with the proper operation of the 30 parts due to the causes above mentioned.

A further object is to provide an attachment which is simple and inexpensive, can be applied readily, and will not interfere with the operation of any of the parts of the 35 machine.

With the foregoing and other objects in view, which will appear as the description proceeds, the invention resides in the combination and arrangement of parts and in 40 the details of construction hereinafter described and claimed, it being understood that, within the scope of what is claimed, changes in the precise embodiment of the invention shown can be made without departing from 45 the spirit of the invention.

In the accompanying drawings the preferred form of the invention has been shown.

In said drawings

Figure 1 is a plan view of a portion of the 50 machine and showing the attachment in position.

Fig. 2 is a section on line 2—2, Fig. 1.

Fig. 3 is a front elevation of a portion of the machine with the attachment in place.

55 Fig. 4 is a side elevation of the attachment. Referring to the figures by characters of

reference A designates a portion of the usual carriage or totalizer truck for supporting the totalizers of a "Wahl" machine. This totalizer truck or carriage is supported by arms B 60 extending in opposite directions therefrom and having vertical slots C through which extend small screws D extending from the main or typewriter carriage on which the totalizing mechanism is mounted and a portion 65 of which has been indicated at E. The foregoing structure has been clearly disclosed in the patent to Webster No. 968,103 of Aug. 23, 1910.

The attachment constituting the present 70 invention is in the form of two brackets each comprising a base 1, an upwardly extending portion 2, and a head 3. The base is attached by screws or the like to the carriage E while slidably mounted in the head is a screw 4 to 75 the lower end of which is attached the upper end of a coiled spring 5. The lower end of the spring is attached to the arm B thereunder. A nut 6 engages the screw 4 and by means thereof the screw can be raised or 80 lowered thereby to adjust the totalizer truck or carriage A upwardly or downwardly as desired.

In using the structure it has been found that as totalizers are added to the truck, the 85 screws 4 can be adjusted upwardly by means of the nuts 6, thus to pull through the springs 5 upon the arms B, thereby to offset the increased weight and insure continued correct operation of the parts.

90 The attachment can be applied readily to machines already in use and by actual practice has been found to materially increase the efficiency of machines thus supplied.

What is claimed is:

95 In a combined typewriting and computing machine, the combination with the carriage of the typewriter, a totalizer truck associated therewith, oppositely extending arms on said truck and guides permitting said arms a limited vertical movement, of brackets attached to said carriage and overhanging said arms, and an adjustable spring connection between each arm and the adjacent bracket.

100 In testimony that I claim the foregoing as 105 my own, I have hereto affixed my signature in the presence of two witnesses.

SAMUEL H. McCACKEN.

Witnesses:

V. A. DEAN,
G. H. BIGELOW.
